(57) **CLAIM**

The ornamental design for a stenographic tabletop, as shown and described.

DESCRIPTION

FIG. 1 is a rear, top and left side perspective view of our design for a stenographic tabletop;

FIG. 2 is a top plan view thereof;

FIG. 3 is a bottom view thereof;

FIG. 4 is a rear elevation view thereof;

FIG. 5 is a front elevation view thereof;

FIG. 6 is a right side elevation view thereof;

FIG. 7 is a left side elevation view thereof; and,

FIG. 8 is a view as in FIG. 1 wherein an extension on the tabletop is repositioned to a stored state.

The portion of the stenographic tabletop shown in dotted lines does not constitute a part of the claimed design.
